FIG. 1.

FIG. 2.

FIG. 3.

INVENTOR:

William A. Dobson

BY

A. B. Stickney

ATTORNEY.

UNITED STATES PATENT OFFICE.

WILLIAM A. DOBSON, OF HARTFORD, CONNECTICUT, ASSIGNEE TO UNDERWOOD TYPEWRITER COMPANY, OF NEW YORK, N. Y., A CORPORATION OF DELAWARE.

TYPEWRITING MACHINE.

1,418,241.

Specification of Letters Patent. Patented May 30, 1922.

Application filed April 30, 1920. Serial No. 377,750.

To all whom it may concern:

Be it known that I, WILLIAM A. DOBSON, a citizen of the United States, residing in Hartford, in the county of Hartford and State of Connecticut, have invented certain new and useful Improvements in Typewriting Machines, of which the following is a specification.

This invention relates to typewriting machines, such as the Underwood portable typewriting machine disclosed in my Patent No. 1,335,956, dated April 6, 1920. In such and other machines, the case-shift mechanism is preferably adapted to be locked in the shifted position to enable upper-case types to print, as is also true in the larger machines. In these small machines, however, since the mechanism is necessarily built of small parts, certain difficulties arise in making the case-shift lock work satisfactorily. In the larger machines, a case-shift lock can usually be adapted to hold the case-shift mechanism at the limit of its throw, even if the lock has a little lost motion, because the length of the key-lever allows the key-lever to spring sufficiently to take up the required lost motion, without involving any movement of the case-shift mechanism proper. Locks, like those used in the larger machines, require so much lost motion that the key-levers of the small machines are too short to absorb it in springing, with the result that the types, actuated when the case-shift lock is effective, are out of alignment with those actuated when the case-shift is manually held effective. Moreover, in small machines, if the desired portability is to be retained, the parts must be kept as light as possible and yet have the requisite stiffness.

To obtain uniform alignment at the case-shift operation, it has been found sufficient to provide a lock-arm for the case-shift key, which, when swung to effective position, engages the case-shift key-lever by friction and holds it substantially without movement, while pressure upon the case-shift key is sufficient to allow the lock to be released. It has been found possible to obtain this result by providing a lock-arm which swings over a lug on the case-shift key, in such a manner that the arm, instead of engaging over the lug, so that a substantial depression of the case shift key would be necessary to release the arm, engages there-with with sufficient friction to be retained

against the tension of the spring, which normally tends to make the arm ineffective. Pressure upon the key will cause the key-lever to yield slightly, but sufficiently to enable its lug to release the arm.

60

To make such a mechanism a practical commercial article, it has been found that the lug must be slightly adjustable upon the key-lever to allow for slight inequalities in the stamping or in the final shaping of the parts, since the adjustments are necessarily very fine.

65

According to the present invention, the lug, instead of being fast upon the key-lever, may be movable thereon, and, in the form herein illustrated, is shown as part of a member pivoted upon the key-lever and provided with an adjusting screw adapted to be variably set to co-operate with the lock-arm. Since the machine in the patent above referred to has two shift-key-levers shifting to different cases, each lever may have its lug upon such a pivoted member, and adjustable in the manner described.

70

Other features and advantages will hereinafter appear.

In the accompanying drawings,

Figure 1 is a perspective view of a pair of shift-key-levers of the kind described, showing the present invention as applied thereto.

75

Figure 2 is a side view of the same, showing parts in normal position.

Figure 3 is a view similar to Figure 2, but showing the figure shift-key depressed and locked.

80

In the Underwood standard portable typewriting machine, the character-keys 1 may be used to print either in lower case, capital case, or figure case, by means of types not shown herein. Normally they print in lower case. When it is desired to print in the figure case, which is the highest case, the figure shift-key 2 is depressed to swing its key-lever 3 around its pivot 4, so that the rear end 5 of the key-lever lifts a rock-arm 6, which is adapted to lift the shift-frame 7 of the typewriting machine from its normal Figure 2 position to the Figure 3 position. In doing this, the figure shift-key 2 causes a lug 8 near the rear end of its key-lever to lift a rock arm 9, and rock to ineffective position a capital-shift stop 10, which normally is adapted to arrest the shift-frame 7 when the capital-shift-key is depressed. The rock-

100

105

110

ing carries the stop 10 clear of the shift-frame and allows the shift-frame to rise until a lip 11 thereon strikes the figure-case-shift-stop 12.

- 5 When in the Figure 3 position, the shift-key 2 is adapted to be locked by depression of a finger-piece 13, formed as a rock-arm having a lower extension or arm 14, which, at the depression of the finger-piece, swings 10 forwardly over a lug 15 on the key-lever 3. When the key-lever 3 is in its Figure 3 position, the lower end 16 of the arm 14 frictionally engages the point 17 of the lug 15, and is held there by friction against the tension of the spring 18, which normally tends 15 to return the arm 14 and finger-piece 13.

To enable the accurate adjustment of the lug 15 to hold the arm 14, the lug is formed as a rear end of a member 19, pivoted at 20 20 upon the key-lever 3, and the lug is adapted to be shifted or raised by turning a screw 21 threaded into a lip 22 on the member 19, overlying the key-lever 3. It has been found sufficient to rely upon gravity or friction to 25 hold the member 19 down upon the key-lever. The arm 14 is behind a front plate 23 of the typewriting machine, and the member 19 extends from in front of the plate to the back thereof, thus rendering it easy to adjust the screw 21 without disassembling the 30 machine at all.

The capital-shift-key 24 is adapted to be locked in the same way by a locking arm 25 which may be formed out of the same flat 35 piece of metal as the arm 14, and may be connected thereto by a bent-over rocking bail 26. The capital-shift-key 24 is provided with a lug 27 which may be like the lug 15, being the rear end of a member 28, pivoted at 29 upon the key-lever 30 of the shift-key 24, which, like the key-lever 3, is pivoted at 4. The arms 14 and 25 may be journaled upon a shaft 31, mounted in brackets 32 on the rear side of the plate 23. Since the bottom 45 16 of the arm 14 and the bottom 33 of the arm 25 are about concentric with the shaft 31, depressing either the key 2 or the key 24 will relieve the pressure of its lug on its arm sufficiently to allow the spring 50 18 to return the arms to ineffective position and release the key.

Variations may be resorted to within the scope of the invention, and portions of the improvements may be used without others.

55 Having thus described my invention, I claim:

1. In a typewriting machine having a front wall, in combination, a case-shift mechanism, a case-shift key-lever projecting 60 through said front wall, a movable locking member back of the front wall, a lug back of said wall and shiftably supported on said key-lever, and means actuatable at the front of said wall for variably adjusting the lug 65 on the lever.

2. In a typewriting machine having a front wall, in combination, a case-shift mechanism, a case-shift key-lever projecting through said front wall, a movable locking member back of the front wall, a lug back 70 of said wall and shiftably supported on said key-lever, means actuatable at the front of said wall for variably adjusting the lug on the lever, means normally urging said locking member to ineffective position, and 75 means actuatable at the front of said wall for shifting said locking member to effective position.

3. In a typewriting machine, the combination with a case-shift mechanism, of a case- 80 shift key-lever, a locking arm for said lever, a stop for arresting the throw of the lever, a member pivoted to swing on the lever, a lip on said member overhanging the lever, a screw threaded into the lip to bear against 85 the lever to limit the throw of the member, and a lug on the member adapted to be engaged by the arm to lock the lever.

4. In a typewriting machine, the combination with a case-shift mechanism, of a pair 90 of case-shift key-levers, a locking arm for each lever, a single finger-piece for shifting said arms into their effective positions, a stop for arresting the throw of each lever, a lug on each lever adapted to be caught by 95 its arm, and means for independently and variably positioning the lugs on their levers.

5. In a typewriting machine, the combination with a case-shift mechanism, of a pair 100 of case-shift key-levers, a locking arm for each lever, a single finger-piece for shifting said arms, a stop for arresting the throw of each lever, a member on each lever and pivoted to swing thereon, means for limiting the swinging of each member on its 105 lever, and a lug on each member adapted to be engaged by the corresponding arm to lock the lever.

6. In a typewriting machine, the combination with a case-shift mechanism, of a pair 110 of case-shift key-levers, a locking arm for each lever, a single finger-piece for shifting said arms, a stop for arresting the throw of each lever, a member on each lever and pivoted to swing thereon, a lip on each member 115 overhanging its lever, a screw threaded into each lever to limit the throw of its member, and a lug on each member adapted to be engaged by the arm to lock its lever.

7. In a typewriting machine, the combination with a case-shift mechanism, of a pair 120 of case-shift levers adjacent each other, an adjustable lug on each lever, an arm for each lever adapted to be swung to frictionally engage said lugs, a rock member for said arms above the levers, a spring normally tending to release the arms, and a finger-piece fast on the member whereby the arms 125 may be made effective.

8. In a typewriting machine, the combina- 130

- tion with a case-shift mechanism, of a pair of case-shift levers adjacent each other, an arm for each lever, a rock member to which said arms are fast, a lug on each lever adapted to be frictionally engaged by its arm to lock the lever down, means for separately adjusting each lug, and a finger-piece fast on said member to move the arms to effective position.
10. In a typewriting machine having a front wall, in combination, a case-shift mechanism, a case-shift key-lever projecting through said front wall, a movable locking member back of the front wall, a lug back 15 of said wall and shiftably supported on said key-lever, means actuatable at the front of
- said wall for variably adjusting the lug on the lever, means normally urging said locking member to ineffective position, and means actuatable at the front of said wall for shifting said locking member to effective position, the co-operating surfaces on said locking member and lug being such that the friction therebetween will maintain the locking member in effective position but a slight depression of said key-lever will permit said member to return to its normal position.

WILLIAM A. DOBSON.
